(57) **CLAIM**

We claim the ornamental design for a powerhead, as shown and described.

DESCRIPTION

FIG. 1 is a front-left perspective view from above of the claimed design according to one embodiment;

FIG. 2 is a front view of the claimed design of FIG. 1;

FIG. 3 is a rear view of the claimed design of FIG. 1;

FIG. 4 is a right side view of the claimed design of FIG. 1;

FIG. 5 is a left side view of the claimed design of FIG. 1;

FIG. 6 is a top view of the claimed design of FIG. 1;

FIG. 7 is a bottom view of the claimed design of FIG. 1;

FIG. 8 is a front-left perspective view from above of the claimed design according to one embodiment;

FIG. 9 is a front view of the claimed design of FIG. 8;

FIG. 10 is a rear view of the claimed design of FIG. 8;

FIG. 11 is a right side view of the claimed design of FIG. 8;

FIG. 12 is a left side view of the claimed design of FIG. 8;

FIG. 13 is a top view of the claimed design of FIG. 8;

FIG. 14 is a bottom view of the claimed design of FIG. 8;

FIG. 15 is a front-left perspective view from above of the claimed design according to one embodiment;

FIG. 16 is a front view of the claimed design of FIG. 15;

FIG. 17 is a rear view of the claimed design of FIG. 15;

FIG. 18 is a right side view of the claimed design of FIG. 15;

FIG. 19 is a left side view of the claimed design of FIG. 15;

FIG. 20 is a top view of the claimed design of FIG. 15; and,

FIG. 21 is a bottom view of the claimed design of FIG. 15.

The broken lines showing portions of the powerhead in the drawings form no part of the claimed design. Broken lines formed by equal length dashes show unclaimed portions of the design. Broken lines formed of unequal length dashes (i.e., dash-dot) show boundaries between claimed and unclaimed portions of the design.

1 Claim, 21 Drawing Sheets
